UNITED STATES PATENT OFFICE.

JOSEPH L. HOFFMAN, OF PORTLAND, OREGON.

OIL-BURNER.

1,186,193.

Specification of Letters Patent.

Patented June 6, 1916.

Application filed December 10, 1914. Serial No. 876,418.

To all whom it may concern:

Be it known that I, JOSEPH L. HOFFMAN, a citizen of the United States, residing in the city of Portland, county of Multnomah, and State of Oregon, have invented certain new and useful Improvements in Oil-Burners, of which the following is a specification.

My invention relates to oil burners of the type adapted for burning oil mixed with steam, and has among its salient objects to provide certain improvements in the construction and arrangement thereof whereby I am able with a single operating member to simultaneously regulate the feed of the oil and steam into the mixing chamber, and also to operate the members which regulate the discharge from the burner, thereby providing a construction which makes more easily possible and practical the automatic control of the burner; to provide a construction of the character referred to in which all of the controlling members are also adjustably secured to the operating member, whereby to make possible an adjustment of each member relative to the opening or outlet which it controls; and, in general, to provide in an oil burner of the character referred to a simplified and improved construction, whereby greater efficiency can be secured because of better regulation, and whereby suitable means for automatically controlling the same can be very conveniently adapted thereto.

In order that others may thoroughly understand my improved burner, I have shown in the accompanying sheet of drawings one practical embodiment thereof which I will now describe, and in which,—

Figure 1 is a longitudinal sectional view thereof; Fig. 2 is a horizontal sectional view thereof taken on line 2—2 of Fig. 1; Fig. 3 is a cross sectional view thereof taken on line 3—3 of Fig. 1; Fig. 4 is a side elevation of my burner connected up with supply pipes for oil and steam, and showing one means for automatically operating the same.

Referring now more in detail to the drawings, the burner A comprises three parts, a combination attaching and mixing member 1, a middle body portion 2, and a discharge cap 3. The attaching and mixing member 1 is threaded interiorly, as at 1^a, to receive the end of a steam pipe 4, and is also threaded interiorly, forwardly of said first threads, as at 1^b, to receive the end of an oil

pipe 5, whereby said oil and steam pipes are mounted one within the other and each is independently connected to the burner body member 1. The forward end of said body portion 1 is reduced and threaded exteriorly, as at 1^c, whereby to be connected into the middle body portion 2, as indicated. The member 1 is provided therethrough with a series of steam passageways, as 1^d, leading from the discharge end of the steam pipe 4, as indicated. Said member 1 is also provided therethrough with a series of oil discharge passageways, 1^e, leading from the discharge end of the oil supply pipe 5, as indicated. Said body member 1 is also extended into a tapered portion, as 1', as shown. Mounted through said oil supply pipe 5 and through said burner is an operating rod or member 6, threaded through the extension 1', whereby said rod can be moved longitudinally through the burner by turning, though it is evident that the threads might be omitted and a sliding fit provided for the rod 6 within the extension 1', if desired. Secured upon said rod 6, by means of lock nut 7, is a deflecting member 8, adapted to fit into the end of the extension 1', which is formed accordingly, whereby to regulate the discharge openings of the oil passageways 1^e, as said operating rod 6 is moved in one direction or the other, as clearly indicated. Also mounted upon said operating rod 6, to move therewith, is a chambered member 9, adjustably secured in place by means of lock nuts 9'—9", said member 9 being adapted to slidably fit within the middle body portion 2, and having one end constructed to fit over the tapered extension 1', as at 9^a, and flaring outwardly in its interior to receive the discharge from the steam passageways 1^d, through the member 1, as indicated. As said member 9 is moved rearwardly by said operating rod 6, the open end thereof moves over the tapered portion 1', at 9^a, in such manner as to close the annular passageway therebetween, and as it is moved forwardly, said passageway is opened because of the taper of the member 1'.

The forward end of the chambered member 9 is provided with a series of discharge passageways, 9^b, discharging into a second mixing chamber 10, formed between the member 9 and the conical closure member 11, mounted upon the rod 6 and secured thereto by means of lock nuts 12—12, said

conical member being adapted to close or regulate the annular opening therearound from the end of the middle body member 2, as at 2^a, and the discharge into the cap 3.

5 The discharge cap 3 is provided with a transversely extending slot or opening 3^a into which fits a U-shaped wedge member 3^b, loosely secured to the end of the rod 6, and adapted to move therewith, whereby to

10 open and close or regulate the discharge opening 3^a from the discharge cap 3. Thus it will be noted that any movement of the operating rod 6 longitudinally through the burner simultaneously moves the deflecting member 8, the chambered member 9, the conical member 11, and the U-shaped member 3^b, either outwardly or inwardly, as said rod 6 is moved, and thereby simultaneously regulates all of the feed openings into the

15 several mixing chambers, the deflecting member 8 and the chambered member 9 controlling the inlet of steam and oil into the mixing chamber in the member 9, while the conical member 11 controls the passage of

20 the mixed oil and steam from said second mixing chamber 10, and the U-shaped member controls the final discharge from the burner cap 3. The discharge passageways 1^d, 1^e and 9^b are preferably arranged so as

25 to make their discharges in a whirling or mixing manner and thereby more thoroughly mix the oil and steam for combustion purposes. I have also illustrated in Fig. 1, one means for automatically operating the op-

30 erating rod 6, which consists in providing it with a gear 13, adapted to be engaged and operated by a rack 14, which may be connected to and operated from any suitable heat or pressure-controlled regulating member.

35 I have shown an expansion member 15, adapted, as at 15' to be connected with the boiler, whereby the pressure in the boiler operates to expand said member 15 and thereby move the operating rack 14 and op-

40 erate the rod 6, in a manner which will be readily understood. Thus by the simple movement of a single operating member, the rod 6, I am able to make a plurality of ad-

45 justments and regulations and control both the flow of the steam and the oil, as well as the discharge from the burner into the combustion chamber in which it may be set.

50 I am aware that changes can be made in the form of the invention here shown for illustrative purposes without departing from the spirit thereof, and I do not, therefore, limit the invention to these details, except as I may be limited by the language of the hereto appended claims.

55

60 I claim,—

1. An oil burner comprising a hollow body having connections for oil and atomizing fluid supply pipes, separate series of small passageways communicating with the interior of said body and with the respective

supply pipes, controlling members for said series of passageways, the outer of said members forming a mixing chamber, outlets from said mixing chamber communicating with the discharge end of the burner, and means for simultaneously operating said controlling members. 70

2. An oil burner comprising a hollow body having connections for oil and atomizing fluid supply pipes, separate series of small passageways communicating with the interior of said body and with the respective supply pipes, controlling members for said series of passageways, the outer of said members forming a mixing chamber, outlets from said mixing chamber communicating with the discharge end of the burner, a controlling member for the discharge end of the burner, and means for simultaneously operating all of said controlling members. 85

3. An oil burner comprising a hollow burner body, means for connecting oil and atomizing fluid supply pipes thereto, a plurality of controlling members movably mounted in said body, one of said controlling members having formed therein a mixing chamber with inlets and outlets therefor, and an operating rod extending longitudinally through said burner and upon which said controlling members are mounted, whereby to be simultaneously moved to control the passage of the fuel through said burner body. 90

4. An oil burner comprising a hollow burner body, means for connecting oil and atomizing fluid supply pipes thereto, a plurality of controlling members movably mounted in said body, one of said controlling members having formed therein a mixing chamber with inlets thereto and outlets therefrom, a controlling member movably mounted to control the discharge opening from said oil burner, and an operating rod extending longitudinally through said burner and upon which all of said controlling members are mounted, whereby to be simultaneously moved to control the passage of the fuel through said burner body. 105

5. An oil burner comprising a hollow body having connections for oil and atomizing fluid supply pipes thereto, one within the other, with separate series of small passageways communicating with the interior of said body and with the respective supply pipes, controlling members for said series of passageways, the outer of said members forming a mixing chamber with outlets therefrom, an operating member mounted longitudinally through said inner supply pipe and said burner body, and upon which said controlling members are secured to move therewith for controlling the passage of fuel through said burner, and a controlling member mounted upon the end of said operating member in the discharge opening 115 120 125 130

of said burner, whereby the movement of said operating member simultaneously moves all of said controlling members.

6. A oil burner comprising in combination 5 a body having connections for oil and steam pipes arranged one within the other, a chambered member movably mounted within said body, said body having series of small passageways communicating with the oil and 10 steam pipes and discharging into said chambered member, and an operating member within said burner body for moving said chambered member, the latter being provided with a series of discharge passageways 15 at its outer end, and means for regulating the discharge from said burner body.

7. In an oil burner, in combination, a coupling member having connections for oil and steam pipes arranged one within the 20 other and having a series of small passageways therethrough for each pipe connection, a body connected to said coupling member, a cap for said body and provided with a discharge opening, an operating rod mov- 25 ably mounted longitudinally through said burner, a controlling member with mixing chamber therein mounted on said rod and movable therewith and into which said small passageways discharge, said member hav- 30 ing a series of passageways from its opposite end, and a controlling member mounted on said rod in the discharge opening from said cap and movable by said rod, substantially as described.

8. In an oil burner, in combination, a body having a coupling member with a tapered extension and connections for oil and steam pipes arranged one within the other, said coupling member having a series of 40 small passageways therethrough for each pipe connection discharging into the interior of said body, said body having a discharge opening at one end, an operating rod through said burner body, a member thereon 45 for controlling the oil passageways, a member thereon for controlling the steam supply, and a member thereon for regulating the discharge opening from said burner body, all of said members being movable with said 50 operating rod to simultaneously regulate said passageways and opening, substantially as described.

9. In an oil burner of the character described, a coupling member having oil and 55 steam pipe connections, arranged one within the other and having a series of passageways therethrough for each pipe connection, a body portion, and a cap mounted on said body portion with discharge opening there- 60 in, an operating rod extending longitudinally through said burner, a part on said

rod for controlling the oil passageways a chambered member mounted on said rod and moving therewith and adapted to control the steam supply through the steam 65 passageways, and into which said oil and steam passageways discharge, and a member mounted on said rod in the discharge opening in said cap for simultaneously regulating the discharge opening with the regulating of the steam and oil passageways, substantially as described.

10. In an oil burner, in combination, a coupling member having oil and steam pipe connections, arranged one within the other 75 and having a series of passageways therethrough for each pipe connection, a body portion, and a cap with discharge opening therein, an operating rod extending longitudinally through said burner, a part on 80 said rod adapted to control the oil passageways, a part on said rod adapted to control the steam supply from said steam passageways, a member controlling the passageway into said cap, and a member in the discharge 85 opening of said cap for regulating the same, all of said parts and members moving with said operating rod and adapted to simultaneously change their positions with the movement of said rod.

11. In an oil burner of the character described, in combination, a coupling portion having oil and steam pipe connections arranged one within the other, and having two series of passageways therethrough, one se- 95 ries for the steam and one for the oil, a main body portion connected to said coupling portion, a cap with discharge opening therein connected to said main body portion, an operating rod extending through said burner 100 and movable longitudinally therein, a part mounted thereon and positioned to control the discharge ends of the passageways leading from the oil supply, a part mounted thereon and positioned to control the dis- 105 charge ends of the passageways leading from the steam supply, a part thereon adapted to control the passage into said cap, and a part thereon adapted to control the discharge opening of said cap, all of said parts 110 being adjustably secured to and moving with said operating rod, and means for moving said rod longitudinally within said burner, whereby to simultaneously regulate the various passageways through said burner, sub- 115 stantially as described.

Signed at Portland, Multnomah county, Oregon, this 4th day of December, 1914.

JOSEPH L. HOFFMAN.
